UNITED STATES PATENT OFFICE.

FERDINAND SCHMIDT, OF DES MOINES, IOWA.

DESIGN FOR A GRAVY BOAT OR SIMILAR ARTICLE.

Application filed November 5, 1926. Serial No. 19,619. Term of patent 7 years.

To all whom it may concern:

Be it known that I, FERDINAND SCHMIDT, a citizen of the United States, and a resident of Des Moines, in the county of Polk and State of Iowa, have invented a certain new, original, and ornamental Design for a Gravy Boat or Similar Article, of which the following is a specification, reference being had to the accompanying drawing, forming part thereof.

Figure 1 is a side elevation, partly in section of a gravy boat or similar article showing my new design; and

Figure 2 is a fragmentary plan view of the plate portion of the same.

I claim:

The ornamental design for a gravy boat or similar article, as shown.

Des Moines, Iowa, October 14, 1926.

FERDINAND SCHMIDT.
